Primary Examiner — Jeffrey D Asch*Assistant Examiner* — Rebekah A Caruso(74) *Attorney, Agent, or Firm* — Carter, DeLuca, Farrell & Schmidt, LLP(57) **CLAIM**

The ornamental design for an insect trap, as shown and described.

DESCRIPTION

FIG. 1 is a front perspective view of an insect trap in accordance with the present design;

FIG. 2 is a right side elevational view thereof;

FIG. 3 is a left side elevational view thereof;

FIG. 4 is a front side elevational view thereof;

FIG. 5 is a rear side elevational view thereof;

FIG. 6 is a top plan view thereof; and,

FIG. 7 is a bottom plan view thereof.

The broken lines shown in the figures that are immediately adjacent to the shaded areas and define unshaded regions represent the bounds of the claim. All other broken lines, including the features within broken line boundaries and the outlines of triangles on the center section, are directed to environment. The broken lines form no part of the claimed design.
